UNITED STATES PATENT OFFICE

HENRI CHARLES LAENGEL, OF PARIS, FRANCE

AUTOMATIC FIRE EXTINGUISHER

Application filed December 19, 1927, Serial No. 241,197, and in France December 24, 1926.

The apparatus according to the invention consists of an automatic fire extinguisher which is chiefly adapted for use upon motor cars and aeroplanes.

5 The said apparatus is preferably placed adjacent the carburetor, and in the case of improper heating, back firing, or any other action causing fire, the apparatus will act automatically, and without the aid of the 10 driver or the pilot, to put out the fire. In this manner, the fire cannot reach the fuel tank, so that there will be no danger of an explosion which would destroy the vehicle or the aeroplane. The said automatic extinguisher is also adapted for use upon all apparatus or machines, and in all places in which flames might be communicated to tanks, cisterns, storage plants or the like, thus setting fire to the same.

15 20 The said invention consists in the use of a suitable cap, disc, washer or the like, consisting of an inflammable substance or composition, such as celluloid, whose combustion will take place at a given temperature. When 25 the said cap (or the like) is consumed, it will release in an entirely automatic manner the devices whereby the fire extinguisher is set in action.

By way of example, an apparatus based on 30 these principles is shown in the appended drawings, in which the dimensions which have been herein selected for the use of the apparatus upon motor vehicles or the like, will obviously vary with the use which is to be made of the said apparatus.

Fig. 1 is a vertical sectional view of the apparatus.

Fig. 2 is a partial section showing the means for supporting the mechanism in the 40 container.

Fig. 3 is a sectional view of the lower part of said apparatus showing the displacement of the parts after the burning of the cap and the exit of the extinguishing liquid when 45 charged by the impelling gas.

Fig. 4 shows the mechanism of said cap in the released position.

Fig. 5 is a sectional view on a larger scale of a modified form of construction.

50 The said apparatus comprises a container

1 which is closed at the top by a cover 23 which may be screwed, crimped, soldered or the like. At the lower part of said container is a seat 19 for a valve 6 carried by a rod having an upper pointed end 5.

55 The percussion mechanism consists of three telescoping members 4—15—16; the member 16 supports the whole mechanism and is held in said container by two rods 21 secured to the cover 23.

60 This said mechanism consists in the percussion member 4 having a central transverse opening and a pointed end adapted to rupture the gas filled cartridge. The lower end of the member 4 telescopes into the member 15 which houses a coiled spring which bears against the member 4. The intermediate member 15 has at its upper end two arms diametrically opposite and extending outward at an acute angle and each pivotally supporting a wing shaped trigger 14. Extending at right angles from the member 15 are supports engaging bolts 21 which support the said percussion mechanism. The member 16 which telescopically houses the member 15 65 has two upstanding portions which engage the triggers and hold the mechanism in cocked position. Formed in the side of the member 16 are slots 17 in which pins 18 on the intermediate member travel, thereby limiting 70 the relative movement of the members 15 and 16.

75 The whole mechanism is held in the inoperative position by the pointed member 5 which is secured against movement by the combustible or fusible cap 8. The said cap thus holds the whole mechanism in the cocked position, and when it disappears (by combustion) the apparatus will operate. The pointed member 5 carries, as stated, a valve 6 which fits 80 tightly upon the seat 19 of the container, whereby all leakage of the extinguishing liquid is obviated.

85 90 95 The cap 8 is provided with a thickened rim which has screw threads engaging the end of the container. Embedded in the thickened rim are the ends of a metallic band 29 which passes through the celluloid cap and bears against the lower end of the releasing member 5. This prevents too rapid burning 100

of the cap and strengthens the said cap against injury from blows or through falling. Also it prevents the release of the member 5 until the cap is entirely consumed, thereby allowing the liquid to be discharged in all directions.

Connected with the interior of the container through the valve 6 is a sprinkling cap 7 through which the member 5 passes and which is entirely enclosed by the combustible cap 8. The said sprinkling cap is attached by the usual bayonet slot and pins 12. The sprinkling cap being entirely covered by the combustible cap, the possibility of the openings of the said cap being filled with dirt is precluded.

Carried at the top of the container is a carbonic acid gas cartridge which is adapted to be ruptured by the pointed end of the member 4. The said cartridge is covered and supported by a cap 2 threading on the container. The said cap is sealed by a packing member 9 to prevent the escape of the gas.

In operation the cap 8 is entirely consumed by fire and releases the releasing member 5 which is forced downward by the spring 10. The member 16 relieved of the supporting member 5 drops through the action of gravity, releasing the support on the wing shaped triggers 14 which drop and permit the member 4 to be propelled upward by the coiled spring 10, the pointed end rupturing the cartridge and discharging the gas under high pressure into the container. The high pressure of course passes some of the gas into solution and the water is discharged at the spraying cap under pressure.

The liquid is never under pressure, so that there will never be any loss of liquid, or loss of expelling force.

Due to its construction, the said apparatus, even when indented by a shock, will still operate, and in all positions whether vertical, horizontal or inverted. If a motor vehicle should take fire in the hood, the apparatus will come into action.

To reset the device, a new combustible cap is screwed in place forcing the releasing member upward, thereby engaging the member 16 which in turn forces the winged triggers outwardly and draws the member 4 back into cocked position. The cap 2 is then removed and a new cartridge inserted. Thus, by two simple movements the device is again ready for use.

The modification which is shown in Fig. 5 differs from the preceding by the following construction. The compressed gas cartridge is so disposed that when the cartridge is opened the gas will issue above the level of the liquid contained in the apparatus; also, the combustible closing cap is so arranged that it will hold the pointed member in place until it is entirely consumed.

In this modification, the apparatus com-

prises a main body 1 provided with a lower neck 1', closed at the lower end, in which is formed a seat 19 for the valve 6 which is carried by the releasing member 5. The top end 23 is crimped upon the edge of the main body 1, and it is provided with a central tapped hole 25 coating with a member 26 which descends into the main body 1, and forms at its lower part a socket 15 provided with side lugs; carrying the pivot axles for the wing-shaped members 14 whose pointed ends are disposed in an aperture in the heavy member 4' which is upwardly urged by a spring 10 and is slidable in the socket 15. The spring 10 abuts against a pin 18 extending horizontally through the said socket and whose ends project and are guided in vertical slots 17 formed in a cylindrical piece 16 which coacts with said socket and rests at the bottom on the upper end of the pointed member 5, also possessing lugs to support the members 14.

The compressed gas cartridge 3 is vertically placed between the branches of the strap 26 and rests on the member 4'. The end of the cartridge neck thus coincides with the striker point 4 which is vertically mounted at the centre of a screw plug 27 engaged in the tapped aperture 25 in the upper end 23. The said plug 27 is made hollow in such manner as to form a gas bell 28 above the neck of the cartridge 3, between its internal wall and the level of the liquid in the apparatus.

At the lower part of the main body 1, and upon the screw thread of the neck 1', is mounted a sprinkling cap or head 7 of hemispherical shape, which is apertured for the insertion of the lower end of the pointed member 5 which is disposed at the middle part of an arc-shaped spring strip 29 such as a wire, a band or the like, whereby the parts will be fastened. The ends of said curved part 29 are so shaped as to form claws 30. Upon the outer threaded part of the sprinkling device 7 is mounted a ring 31 comprising a lower circular projection 32, annular groove 33 being formed in its upper end, for the insertion of a ring 34 of a combustible or fusible substance which also engages the attaching claws 30 of the spring 29 and holds them upon the circular end portion, the spring 29 being thus placed under tension. The combustible or fusible ring 34 is provided with a cap 8 consisting of a combustible substance which covers and protects the sprinkler 7, the ends of the pointed member 7, and the spring 29.

In the inoperative position of the apparatus, the several parts occupy the positions shown in the drawings.

The operation of the apparatus is as follows.

Upon the first contact with the flame, the cap 8 is consumed, so that the inflammable or

fusible securing ring 34 will be destroyed or broken, thus releasing the ends of the spring 29 which accordingly expands. The claws 30 are disengaged from the end part 32, and the 5 spring 29 no longer acts upon the pointed member 5, so that the valve 6 will allow the liquid to be discharged to the exterior.

At the same time, the descent of the pointed member 5 will cause the descent of the member 16 relatively to the socket 15. The lugs of the member 16 will no longer hold the members 14; the spring 10 impels the member 4' which thus raises the cartridge 3 while at the same time the members 14 are rotated, 15 and they will act upon the member 16 and the pointed member 5 to completely open the passage for the liquid.

At the same time, the cartridge 3 is ruptured by the striker 4; the gas enters the bell 20 formed by the plug 27 and thus forces out the liquid through the valve 19. In this manner the liquid is expelled with violence and is sprayed in the form of a thick cloud through the apertures in the sprinkler 7.

25 The percussion of the cartridge 3 and the opening of the passage 19 for the discharge of the liquid thus form two distinct operations which occur at the same time and cannot take place separately.

30 I claim:

1. An automatic fire extinguisher comprising a liquid container, a percussion mechanism carried by the container, an outlet valve for the liquid, a gas filled cartridge arranged 35 to be ruptured by the mechanism, and a combustible means on the outside of the container which normally holds the valve in closed position and which when subjected to heat releases the percussion mechanism.

40 2. An automatic fire extinguisher comprising a liquid container, a gas filled cartridge carried above the container, the end of the cartridge projecting into the container, a cap fitting over the cartridge and threading on 45 the container, a percussion mechanism for rupturing the cartridge carried in the container, a releasing member holding the mechanism in cocked position, a combustible means holding the releasing member whereby the 50 burning of said means releases said member, and an outlet valve carried by the releasing member.

55 3. An automatic fire extinguisher comprising a liquid container, a gas filled cartridge carried above the container, the end of the cartridge projecting into the container, a cap fitting over the cartridge and threading on the container, a percussion mechanism for 60 rupturing the cartridge carried in the container, a releasing member holding the mechanism in cocked position, a combustible means holding the releasing member whereby the 65 burning of said means releases said member, an outlet valve carried by the releasing mem-

ber, and a spraying cap covering the outlet valve.

4. An automatic fire extinguisher comprising a liquid container, a gas filled cartridge carried by the container and communicating therewith, telescoping members carried 70 interiorly of the container, the intermediate of these members having arms projecting at an acute angle, wing shaped triggers pivotally supported on said arms, a percussion member held in cocked position by the triggers, a releasing member supporting the telescoping members, a combustible cap maintaining the releasing member in position, an outlet valve, a spraying cap covering the valve opening 80 whereby upon burning of the combustible cap, the releasing member is released, allowing the triggers to turn on their pivots releasing the percussion member to rupture the cartridge.

5. An automatic fire extinguisher, comprising a liquid container, a gas filled cartridge associated with the container, a percussion mechanism for rupturing the cartridge carried in the container, a releasing member holding the mechanism in cocked position, a 90 combustible means holding the releasing member whereby the burning of said means releases said member, and an outlet valve carried by the releasing member.

6. An automatic fire extinguisher, comprising a liquid container, a combustible cap on the outside of the container, a valve normally held in closed position by the combustible cap, percussion mechanism in the container and operatively related to said valve to normally urge it to open position, said percussion mechanism including telescoped sections and an interposed spring with actuating arms between the sections, a gas filled cartridge carried by the container above the percussion mechanism, and means between the top of the percussion mechanism and the top of the container for puncturing the gas filled cartridge when the percussion mechanism is released by the combustible cap.

In testimony whereof I affix my signature.

HENRI CHARLES LAENGEL.
